UNITED STATES PATENT OFFICE.

PETER J. LINDGREN, OF DENVER, COLORADO, ASSIGNOR TO J. W. HORNER, OF DENVER, COLORADO.

METAL-CUTTING TOOL.

Application filed April 21, 1924. Serial No. 707,933.

An object of this invention is to provide improved means for cutting circular holes in metal bodies such as the walls and ends of tanks and containers.

5 A further object of this invention is to provide an improved construction for a metal-cutting tool.

A further object of this invention is to provide improved means for retaining a substantially-annular hacksaw in a metal-cutting tool.

10 15 A further object of this invention is to provide means for carrying a drill and a substantially-annular hacksaw in concentric relation, the respective carrying means being separable and distinct from each other and adapted to be assembled and rigidly joined for use.

A further object of this invention is to 20 provide a two-part tool, one part being adapted to carry a hacksaw, the other part being adapted to carry a drill and also to carry the first part, and means for rigidly, yet detachably, connecting said parts, the 25 hacksaw and the drill for conjunctive use.

A further object of this invention is to 30 provide a two-part tool, one part being adapted to carry a drill and having means for securing the part against rotation relative to the drill, the other part being adapted to carry a substantially-annular hacksaw concentric with the drill and also adapted to be mounted on the first part and rigidly, yet detachably, secured thereto, the drill-retaining means also fixing and determining relative rotation of the two parts of the tool.

35 A further object of this invention is to provide a two-part tool, one part being adapted to be mounted rigidly, yet detachably, on and concentric with a drill, said drill being adapted to be mounted removably in an operating device, the other part of the tool being adapted to be mounted on and concentric with the first part and adapted to carry a substantially-annular hacksaw concentric with said drill, there being a common means employed to prevent rotation of the first part on the drill and to prevent rotation of the second part on the first part, there also being means for rigidly, yet detachably connecting the two parts of the tool.

40 45 50 55 A further object of this invention is to provide a two-part tool, one part being

formed with an internal rabbet adapted to receive a substantially-annular hacksaw and also adapted to receive an expansive friction-locking ring within said hacksaw, the other part of the tool being formed with a cone adapted to bear outwardly on the ring and also being formed with a neck or shank adapted to pass through the first part and be so locked thereto and to adjust the pressure of the cone on the ring.

60 65 70 75 80 85 A further object of this invention is to provide a two-part tool, one part being formed with an internal rabbet and a bore centrally of said rabbet, the rabbet being adapted to receive a substantially-annular hacksaw and also adapted to receive an expansive ring within the arc of and pressing outwardly on said hacksaw, the other part of the tool being formed with a neck or shank adapted to pass through the bore of the first part and also formed with a barrel or hub adapted to fit loosely within the first part and, also formed with a cone adapted to engage the interior arc of and outwardly press the expansive ring, and also 80 formed with a radial bore adapted to receive a set screw in turn adapted to engage a drill arranged axially of the second part, the first part being formed with a notch intersecting the rabbet, hacksaw and ring and adapted to receive the set screw, there being means provided for locking the parts together.

90 My invention consists in the construction, arrangement and combination of elements hereinafter set forth, pointed out in the claims and illustrated by the accompanying drawing, in which—

95 Figure 1 is an elevation of the complete tool assembled as required for practical use. Figure 2 is a longitudinal section axially of the same, the drill and set screw being shown in full. Figure 3 is a bottom or cutting end view of the complete tool. Figure 4 is a view similar to Figure 3, the inner 100 part of the tool being removed. Figure 5 is a view similar to Figure 4, the hacksaw and ring being removed. Figure 6 is an elevation of the inner part of the tool removed from the other elements, dotted lines 105 indicating axial and radial bores therein to receive a drill and set screw respectively.

110 In the construction of the tool as shown the numeral 10 designates an outer part or shell, which is generally cylindrical in form

and has an integral nut 11 on one end. The interior of the shell part 10 is circular and of three diameters; being formed with a rabbet 12 at one end, said rabbet having an oblique or inclined bottom forming a trough of annular form; the shell also being formed with an intermediate chamber 13 opening at one end through the rabbet; and the shell also being formed with a central bore 14 opening from the opposite end of the chamber 13. A notch 15 is formed in and radially of the shell 10 and intersects the rabbet 12 and chamber 13. A hacksaw 16, substantially annular in form, is mounted in the rabbet 12 and, because of inherent tendency to expand, bears against the wall of the rabbet, the spaced ends of the hacksaw providing a notch or passage coincident with the notch 15. The toothed margin of the hacksaw is outermost, being spaced from the adjacent end of the shell 10 a distance greater than any contemplated penetration of the saw in a work object, and the inner smooth margin of the hacksaw seats in the bottom 25 of the trough of the rabbet. An expansive spring ring 17, preferably made of round wire, substantially annular in form, is mounted in the trough of the rabbet 12 and bears, by spring pressure, on the inner surface 30 of the hacksaw opposite to and resisted by the wall of the rabbet, the spaced ends of the ring providing a passage coincident with the notch 15. An inner part or core comprises three integral members, viz, a barrel 35 or hub 18 adapted to fit loosely in the chamber 13, a cone 19 at one end of the hub adapted to enter the rabbet 12 and bear against the inner surface of the ring 17, and a stem, neck or shank 20 at the opposite end 40 of the hub adapted to extend through the central bore 14, the latter being threaded to receive a nut 21. The core is formed with an axial bore adapted to receive a drill 22 and also is formed with a radial bore adapted 45 to receive a set-screw 23, the latter bore being threaded. The drill 22 is formed with a flat seat between its ends and the inner end of the set-screw 23 engages said seat and connects the core to the drill in respect 50 of both circumferential and longitudinal movement of either relative to the other. The set-screw 23 is relatively long and is adapted to extend through the notch 15 and through the spaces between the ends of the 55 hacksaw and of the ring 17 and, under some circumstances, such as an overload on the spring ring, said set-screw may be engaged by an end of the hacksaw and limit circumferential movement thereof relative to the shell. Before the nut 21 is applied to the 60 stem 20, the core, with the drill 22 and set-screw 23 assembled therein, may be inserted in the shell so that the set-screw enters the notch 15 and the stem passes through the bore 14, after which the nut is applied and

tightened against the outer end of the shell by a wrench applied thereto, the shell being held stationary by engaging it in a vise or wrench applied to the nut 21 thereon. Tightening of the nut 21 draws the cone 70 19 within and causes it to press outwardly on and expand the ring 17, thereby applying great pressure to the inner surface of the hacksaw and clamping it firmly, throughout its length, to the wall of the 75 rabbet 12, to the end of preventing any circumferential movement of the hacksaw relative to the shell. The drill may be removed and replaced, or substituted by another, without removing the core from the 80 shell, through manipulation of the set-screw 23.

The assembled tool may be employed for cutting a round hole in a work object, such as a boiler, tank or container, by applying 85 to the drill an operating device such as a brace or boring machine or flexible shaft and rotating the tool; a centering hole being first made by the drill and thereafter the drill employed in said hole to guide the 90 hacksaw in cutting on a circle concentric therewith.

It will be noted that the two-part construction of the tool frame supplies definite and positive adjustment of one part relative 95 to the other and like certain adjustment of the friction cone to insure holding the hacksaw in desired place.

I claim as my invention—

1. A metal-cutting tool comprising a two-part frame, one part being adapted to contain and carry a substantially-annular hacksaw radially engaging the inner face thereof, the other part being adapted to contain a drill centrally of the hacksaw, means 100 between said parts acted on by the second part for applying radial pressure to said hacksaw and means for connecting said frame parts.

2. A metal-cutting tool comprising a two-part frame, one part being formed with a rabbet adapted to contain a substantially-annular hacksaw, the other part being mounted axially of the first part and formed 105 with a cone adapted to apply radial pressure to said hacksaw, the inner part also being adapted to contain a drill, and means for connecting said frame parts.

3. A metal-cutting tool comprising a two-part frame, one part being formed with an internal rabbet having a trough in its bottom, a substantially-annular hacksaw mounted in said rabbet and having its toothed margin spaced from the end of the 120 rabbet, an expansive device mounted in said trough and engaging the inner surface of the hacksaw, the other part of the frame being formed with a cone adapted to engage and expand said device, means for connecting 125 said frame parts, and a drill mounted 130

centrally of the inner frame part and axially of the hacksaw.

4. A metal-cutting tool comprising a two-part frame, one part being formed with a chamber and a rabbet and a bore forming a continuous passage through it, a substantially-annular hack-saw mounted in said rabbet and radially engaging the circumferential wall thereof, the other part being formed with a stem adapted to traverse said bore and a hub adapted to enter said chamber and a cone adapted to enter said rabbet and apply radial pressure to said hack-saw, and also formed with a central bore and a radial bore intersecting the central bore, means for connecting said frame parts and separate cutting devices mounted on the respective frame parts.

5. A metal-cutting tool comprising a two-part frame, one part being formed as a shell and the other part as a core, adapted to enter the shell and having a stem extending through the opposite end of the shell, a substantially-annular hacksaw mounted in the shell, a retaining ring mounted within and expansively engaging said hacksaw, the core having a part adapted to expansively engage said ring, a drill mounted in the core axially of the hacksaw and projecting therefrom at both ends, and a nut adapted to be mounted on said stem and adapted to engage the adjacent end of the shell.

6. In a metal-cutting tool, a shell, a substantially-annular hacksaw mounted loosely in and projecting from one end of said shell, a core removably mounted through said shell and adapted to apply outward pressure to said hacksaw, said shell being formed with a radial notch, said core being formed with a central bore and also formed with a

radial bore intersecting said central bore and intersecting said notch, a drill removably and replaceably mounted in the central bore of the core and a set-screw mounted in said radial bore of the core and traversing said notch.

7. In a metal-cutting tool, a shell, a substantially-annular hacksaw mounted in and projecting from one end of said shell, an open ring mounted within said hacksaw, a core mounted through said shell and formed with an expanding face adapted to engage said open ring, said core also being formed with a central bore and a radial bore intersecting it, said shell being formed with a radial notch registering with the radial bore, the spaces between the ends of the saw and between the ends of the open ring registering with said notch, a drill mounted in the central bore and a set screw mounted in the radial bore and extending through the saw and ring spaces, together with means for connecting said shell and bore.

8. A metal-cutting tool comprising a two-part frame, one part being formed with an internal rabbet, a substantially-annular hack-saw mounted in said rabbet, an expansive device mounted in said rabbet and radially engaging the inner surface of said hack-saw, the other part of the frame being formed with a device adapted to engage and radially expand said expansive device, means for connecting said parts, and a drill mounted centrally of the inner frame part and axially of the hack-saw.

Signed at Denver, in the county of Denver and State of Colorado, this 18th day of April, 1924.

PETER J. LINDGREN.
